Application September 28, 1939, Serial No. 296,960

5 Claims. (Cl. 66—149)

This invention relates to fabric producing machines having a fabric supplying mechanism and is concerned more particularly with an automatic device for advancing the fabric from the supplying mechanism of such a machine and winding it into a roll.

The fabric advancing apparatus employed with certain types of fabric producing machinery, such, for example, as warp knitting machines, have heretofore commonly included a roller which contacts with the fabric being supplied and is rotated by a weight to draw the fabric along. The weight is secured to one end of a rope wound on a drum mounted on the roller and the other end of the rope is attached to the drum. The drum is connected to the roller by a ratchet wheel and pawl connection so that as the rope is unwound from the drum by the descending weight, the roller is driven in one direction and thereby advances the fabric.

In such apparatus, the descending weight reaches the lower end of its path of travel at repeated intervals in winding up a roll of fabric and each time that this occurs, the weight must be restored to its initial position. For this purpose, the drum is provided with a handle by which it may be rotated in the proper direction to wind the rope, and during this operation, the roller is held stationary. The frequency with which the operations of restoring the weight to its initial position occur depends on the size of the drum, the length of rope employed, and the speed with which the fabric is supplied.

The prior apparatus is objectionable in that during the restorations of the weight to its initial position which must be made several times during the winding up of a roll of fabric, the fabric advancing roller is held stationary and the tension on the fabric being supplied is reduced. Such reduction in tension impairs the quality of the fabric and causes "stop marks" to occur in the goods. The take-up device, therefore, does not advance the fabric under constant tension throughout the winding of a roll, as is desired.

In the apparatus described, it has been common practice to wind the fabric into a roll on the advancing roller, but this is objectionable because as the roll of fabric increases in diameter, the roller becomes increasingly effective in applying tension to the fabric being drawn from the supplying mechanism. To overcome this difficulty, attempts have been made to vary the size of the weight acting on the roller during the production of a roll of fabric so that the weight will be progressively decreased as the di-

ameter of the wound roll increases. Such adjustment by hand of the size of the weight is necessarily slow and it cannot be satisfactorily carried on in apparatus used with machines producing fabric at high speeds. Also it increases the cost of production and, in addition, the inevitable variations in the tension on the fabric impair the quality of the latter.

Various devices have been proposed to overcome these difficulties, but each such device with which we are familiar is complicated and expensive to manufacture and operate when employed with high speed fabric producing machines.

15 The present invention is, accordingly, directed to the provision of a novel apparatus for advancing a fabric from its point of production and winding it into a roll, which lacks the objectionable features of the prior devices. The new apparatus is superior to the prior equipment in that it is fully automatic and requires no attention other than initial adjustment. Also it is cheaper to construct and easier to maintain in proper working order and it may be operated 20 with complete satisfaction in connection with machines producing fabric at high output rates.

25 The apparatus of the invention includes a roller which contacts with the fabric and is rotated to advance the fabric from its point of supply and a second roller which rolls up the fabric received from the first roller. The advancing and tensioning roller is driven by means applying a constant and uniform torque thereto so that the fabric is subjected to constant and 30 uniform tension between the roller and the supplying means. The winding roller is driven by means which enable it to wind the fabric received from the first roller without variation in tension on the fabric between the point of supply 35 and the advancing roller arising from the progressive increase in the diameter of the wound roll.

40 For a better understanding of the principles of the invention, reference may be had to the accompanying drawing in which an embodiment of the invention suitable for use with a fabric producing mechanism, such as a warp knitting machine, is illustrated. In the drawing,

45 Fig. 1 is a view of the new apparatus in side elevation; and

50 Fig. 2 is an end view of a detail.

In the apparatus illustrated, the fabric 10 is directed from its point of production over a stationary member, such as a rod 11, and passes therefrom into contact with and partly around

an advancing roller 12 mounted on a shaft 13 supported for rotation in bearings mounted in suitable frame members 14. The shaft is rotated in the proper direction to advance the fabric from its point of production, and to prevent slipping of the fabric relative to the surface of the roller, various expedients may be employed. For some fabrics, the roller may be provided with spikes which engage the fabric, while for others, which would be injured by such spikes, the surface of the roller is roughened or preferably covered with a composition tubing having a roughened surface. A covering of the latter type may consist of a tube made of a material known commercially as "Phenolite" provided with a special finish for the purpose.

From the advancing roller 12, the fabric passes to a take-up roller 15 mounted on a shaft 16 supported for rotation in bearings in suitable frame members 17. The take-up roller is rotated in the proper direction to cause it to wind up the fabric delivered to it by the advancing roller 12. Both rollers 12 and 15 are rotated by automatic devices which cause the roller 12 to advance the fabric at a uniform rate and at a constant tension and cause the roller 15 to wind up the fabric received from roller 12 without affecting the tension in the fabric as it is produced.

The automatic devices for driving the rollers are of similar construction and will be described in detail in connection with the device for driving the roller 12 mounted in the frame 14. Similar reference characters, primed, are used to designate corresponding parts for driving the roller 15 in the frame 17. The automatic driving device for the roller 12 includes a pair of rotary members, such as the sprocket wheels 18 and 19. The sprocket wheel 18 is fast on one end of the shaft 13 and the sprocket wheel 19 is freely rotatable on a pin 20 mounted on one of the frame members 14. Trained around the rotary members 18, 19 is a flexible endless element 21 and when sprocket wheels are used as the rotary members 18, 19, the endless element is a chain. A weight 22 is connected to the chain to impart movement thereto and thereby rotate the members 18, 19 and the roller 12. For this purpose, the chain may be formed with a bight 23 which supports an idler roller 24. The roller 24 is mounted on a pin 25 secured to a plate 26 to which is attached a rod 27 on which the weight 22 is mounted, the rod being guided in its vertical movements by one or more brackets 28 attached to the frame-work of the machine. Also mounted on the pin 25 is a positioning element which may be a roller 29 engaging a track 30 formed by one surface of a member 31 attached to a pin 32 secured to a frame member 14.

The mounting of the weight described is such that it tends to lengthen the bight in the chain and thereby rotate members 18 and 19 and the roller 12. The member 19, however, is held against such rotation, so that the weight is effective only to rotate member 18 and roller 12. Since the roller has a frictional engagement with the fabric, the torque applied to the roller by the weight results in the application of tension to the fabric 10 issuing from the supply mechanism, and since the size of the weight is not changed, once the initial adjustment has been made, the torque is constant and the fabric, therefore, is advanced under uniform tension. When the weight has moved downward a pre-

determined distance by the lengthening of the bight, it must be restored to its initial position and for this purpose, automatic means are provided which produce the desired result without altering the torque applied by the weight to the advancing roller.

The mechanism for periodically shortening the bight in the chain comprises a ratchet wheel 33 connected to the rotary member 19 and free to rotate with that member on the pin 20. Engageable with the teeth of the wheel is a driving pawl 34 which is pivotally connected by a pin 35 to one arm 36 of a bell crank lever pivoted on the pin 20. A spring 37, secured at one end to the arm 36, bears at its other end against the rear surface of the pawl and tends to force the pawl into engagement with the ratchet teeth.

The bell crank lever, to one arm of which the pawl 34 is connected, is continuously rocked and, for this purpose, the second arm 38 of the lever is connected by a link 39 to a crank 40 fast on a shaft 41. This shaft rotates continuously throughout the operation of the machine, but the pawl 34 is kept out of contact with the ratchet wheel except during the periods when the weight is to be restored to its initial raised position. During the period that the weight is descending, the ratchet wheel is held against backward movement by a holding pawl 42 mounted on a pin secured to one of the frame members 14 and held in contact with the surface of the ratchet wheel by a spring 43 connected at one end to the tail of the pawl and at the other to the frame member 14. Since the ratchet wheel is connected to rotary member 19, the latter remains stationary as the weight moves down.

During the descent of the weight, the driving pawl 34 is kept out of engagement with the ratchet wheel by means of a plate 44 which is pivotally mounted on the pin 20 and is formed at one end with a cam surface 45 which engages a cam follower roller 46 mounted on the free end of the pawl. The other end of the plate extends downward beyond the pin 20 and lies in engagement with one or the other of two stops 47, 48, mounted in extensions from the member 31. Between its ends, the plate 44 is provided with an extension 49 carrying a pin to which is connected one end of a spring 50. The other end of the spring is secured to the end of a bar 51 attached to the plate 26 and projecting upwardly therefrom. When the weight is in elevated position, as illustrated, the spring 50 lies above the pin 20 on which the cam plate 44 is pivoted and, consequently, acts to swing the cam plate to a position in which its cam surface has passed beneath the roller 46 and raised the pawl 34 out of operative position and its lower end has come to rest against the stop 47. When the weight has descended a sufficient distance, the point of attachment of spring 50 to bar 51 will have moved downward so that the axis of the spring lies below the pin 20. When the spring thus passes across the axis of oscillation of the cam plate, it swings the plate on pin 20 to move the lower end of the plate from stop 47 to stop 48. In that movement, the cam surface of the plate passes out from beneath the cam follower roller 46 on the pawl 34 and the pawl is moved into engagement with the teeth of the ratchet wheel 33 by the action of spring 37.

In the illustration of the apparatus, the weight is commencing its downward travel and in this condition of the mechanism, the rotary member 19 is held against movement in one direction by

the stop pawl 42 engaging the teeth of the ratchet wheel 33. The weight is, therefore, effective to apply torque to the advancing roller 12 and as the roller is rotated, the bight of the chain lengthens. Also, during such descending movement, the cam plate 44 is effective to maintain the pawl 45 in inoperative condition. When the descent of the weight causes the spring 50 to pass the center of oscillation of cam plate 44, the cam plate is swung by the spring to bring the pawl 34 into operation and the continuously oscillating bell crank 38 causes the pawl to rotate the ratchet 33 in a clockwise direction and thereby rotate the member 19 to take up the chain, shorten the bight, and raise the weight. The raising operation continues until the spring 50 acts to swing the cam plate 44 into the position in which it puts the pawl 34 out of action. Throughout the descent of the weight and its restoration to its initial position, the weight is continuously applying torque to the roller 12 through the sprocket wheel 18 and shaft 13 and, since the weight is not changed in size, the torque thus applied is constant and uniform and a constant and uniform tension is, accordingly, applied to the fabric 10 issuing from the producing machine.

The fabric being advanced by the roller 12 is wound on the take-up roller 15, which may be and preferably is rotated by mechanism similar to that employed for rotating the roller 12. For driving the roller 12, the weight used depends on the tension which it is desired to apply to the fabric and when similar mechanism is employed for rotating the roller 15, the weight used need only be sufficient to cause the take-up roller to wind up the fabric smoothly. As the diameter of the wound roll increases, the size of the weight used for rotating the roller 15 is not changed, but the weight descends more slowly and the mechanism operates less frequently to restore the weight to its initial position. The torque applied to the take-up roller 15 by the weight of its driving mechanism has no effect on the tension applied to the fabric between the roller 12 and the supply mechanism, since the roller 12 has a non-slipping contact with the fabric.

The mechanism of the invention provides a positive means for advancing the fabric from its point of production under constant and uniform tension and the fabric thus advanced is wound into a roll of increasing diameter without effect on the tension in the fabric from its point of production to the advancing roller. The new apparatus may be utilized in connection with fabric producing machines of many types, of which a warp knitting machine is only one example, but it is particularly suited for use with warp knitting machines operating at high speeds. The mechanism has been found to operate more satisfactorily than prior tension and take-up devices and since it is of simple construction and fully automatic, it may be installed and operated at lower cost.

We claim:

1. Apparatus for advancing a fabric under tension which comprises a pair of rollers in contact with the fabric, means for driving one roller to cause it to advance the fabric, and means for driving the other roller to cause it to roll up the fabric delivered to it by the first roller, the driving means for each roller including a pair of rotary members, one of which is connected to the roller to rotate therewith, a flexible endless

element trained about the members, a weight connected to the element and exerting a constant pull thereon which is transmitted to the roller through the rotary member connected therewith and is effective to rotate the roller, the weight descending from an initial position in its operation, means for rotating the second rotary member to move the element to restore the weight to its initial position, and automatically actuated means for controlling the operation of the rotating means.

2. Apparatus for advancing and taking up a fabric which comprises a roller in contact with the fabric, a pair of rotary members, one of which is connected to the roller, a flexible endless element trained about the members and formed with a bight, a weight depending from the bight, means for advancing the second rotary member to shorten the bight and elevate the weight, said means including a ratchet wheel operatively connected to the rotary member and a continuously operating pawl engageable with the ratchet wheel, an element operable to control the action of the pawl on the ratchet wheel and movable between two positions, and a spring attached to the element and actuated by the weight upon a predetermined movement thereof to move the element from one position to the other.

3. Apparatus for advancing and taking up a fabric which comprises a roller in contact with the fabric, a pair of rotary members, one of which is connected to the roller, a flexible endless element trained about the members and formed with a bight, a weight depending from the bight, means for advancing the second rotary member to shorten the bight and elevate the weight, said means including a ratchet wheel operatively connected to the rotary member and a continuously operating pawl engageable with the ratchet wheel, a pivoted cam member movable between two positions and effective in one position to disengage the pawl from the ratchet wheel, the cam member in its other position permitting the pawl to act on the ratchet wheel, and a spring connected to the cam member and to the weight, the axis of the spring being shifted by the weight in its movements to cause the spring to swing the cam member from one position to the other.

4. In a fabric producing machine having a fabric supplying mechanism, a roller for drawing the fabric from the supplying mechanism under tension and a second roller for winding up the fabric received from the first roller, and means for driving one of the rollers including a sprocket wheel connected to the roller, a second sprocket wheel, a chain trained about the sprocket wheels and formed with a bight, and a weight depending from the bight, the combination of a ratchet wheel connected to the second sprocket wheel, a continuously operating spring-pressed pawl engageable with the ratchet wheel to advance it to cause the sprocket wheel to shorten the bight of the chain, a cam for engaging the pawl with and disengaging it from the ratchet wheel, and a spring connected to the weight and operable when the weight reaches predetermined points in its path of travel to act on the cam to cause it to perform its functions.

5. In a fabric producing machine having a fabric supplying mechanism, the combination of a roller for advancing the fabric from the supplying mechanism, a second roller for winding up the fabric received from the first roller, and

means for driving one of the rollers including a sprocket wheel connected to the roller, a second sprocket wheel, a chain trained about the sprocket wheels and formed with a bight, a weight depending from the bight of the chain, a ratchet wheel connected to the second sprocket wheel, a pawl for holding the ratchet wheel against retrograde movement, a driving pawl engageable with the ratchet wheel to cause it to advance and rotate the second sprocket wheel to shorten the bight, an element movable between two positions and effective in its respec-

10 tive positions to disengage the driving pawl from the ratchet wheel and to permit said pawl to engage and drive the ratchet wheel, a connection between the movable element and the weight through which the weight operates upon reaching predetermined movements in its path of travel to move the element from one position to the other, and means for actuating the driving pawl.
